UNITED STATES PATENT OFFICE.

CHARLES BRAND, OF WHITE PLAINS, NEW YORK, ASSIGNOR, BY DIRECT AND MESNE ASSIGNMENTS, TO AJAX-BRAND LOCK CORPORATION, OF NEW YORK, N. Y., A CORPORATION OF NEW YORK.

SAFETY DOOR FASTENER.

Application filed July 23, 1927. Serial No. 207,889.

My invention relates to safety door fasteners and refers particularly to safety door fasteners adapted for use with doors and windows.

5 One of the objects of my invention is a safety door fastener which firmly retains a door, or window, in closed position.

Another object of my invention is a door-lock which allows a door, or window, to be 10 fastened in partly open position.

Another object of my invention is a safety door-fastener which can be positioned for a full opening of a door, or window, only when the door, or window, is in closed position.

15 A burglar-proof safety door fastener, to be effective, must be strong in construction, capable of fastening a door, or window, firmly from intrusion and of such character that it can not be tampered with from the outside.

20 In a broad way, the safety door fastener of my invention comprises a strongly constructed bolt pivotally attached at one end to a door frame, or window frame, the other end of the bolt being removably attached to 25 the door frame, or window frame. The door, or window, carries a pivotal latch, the free end of which is movable within a slot in the bolt and removable therefrom only when the door, or window, is closed. My device also

30 comprises means for fastening it in an extended position when the door, or window, is partly opened. I also enclose means for fastening the elements of my device to the door frame, or window frame, and the door, 35 or window, in such a manner that such fastening means are hidden and difficult, if not impossible, of access from without the door. Further, my device is of such construction that it can be employed with either a right- 40 hand, or left-hand, door, or window.

Among the advantages of my device are the following:

It can not be unfastened from without, either when the door, or window, is in closed 45 position, or in partly open position.

The latch being rigid, the door, or window, is in fixed partly open position, and hence, can be maintained in ventilating position.

50 My device, therefore, acts as a burglar-proof safety door-fastener and as a ventilating device and, when employed in the latter capacity, prevents the opening of the door, or window, and the entrance of an intruder.

The above, and other, valuable features of 55 my device will be evident upon a consideration of this specification and its accompanying drawings.

In the accompanying drawings, illustrating modified forms of the device of my invention, similar parts are designated by similar numerals.

Figure 1 is a front view of a closed door carrying the device of my invention.

Figure 2 is a front view of a closed door 65 carrying the device of my invention, showing that it is reversible from that shown in Figure 1.

Figure 3 is a fragmentary top view of a modified form of latch adaptable where the 70 door and the door frame are in practically the same plane.

Figure 4 is a front view of my device with the door in fastened and closed position.

Figure 5 is a top view with the door in fastened and closed position.

Figure 6 is a top view of my device with the door in fastened and partly opened position.

Figure 7 is a section through line 7—7 of 80 Figure 4.

Figure 8 is a section through the line 8—8 of Figure 4.

Figure 9 is a section through the line 9—9 of Figure 8.

Figure 10 is a top view of a modified form of fastening member.

Figure 11 is a top view of a washer capable of use with my device.

The particular form of the safety door- 90 fastener of my invention, shown in Figures 1, 2, 4, 5, 6, 7, 8 and 9 of the accompanying drawings, comprises a door-frame plate 12, fixedly attached to the door-frame 13 by means of the screws 14, 14, 14 and the screw-eye 15. The screw-eye 15 passes through the rubber noise-absorbing washer 16. The two threaded bolts 17, 17 are then threaded within holes within the extended portion 18 of the plate 12, to prevent the screw-eye 15 from being unscrewed for removal. Additional screws 19, 19 hold the plate 12 to the door-frame 13.

A fastening member consists of a plate 20 having a key-hole opening therein, the larger 105 portion 21 of the opening being above the narrower portion 22. The plate 20 is extended angularly into the portion 23, which

is then extended upwardly into the concave member 24, the latter carrying a knob 25. The fastening member is pivotally attached to the plate 12 and the door-frame 13 by means of a screw 26 carrying the split spring washer 27. The screw 26 has its outer portion cut away into a rectangular shaped member 28 which fits snugly into the opening 22 to prevent the fastening member from swinging when it is in its dependent, or unfastened, position.

A bolt 29 is swingingly carried by the eye-screw 15 by means of the ring 30. The bolt 29 has a longitudinal opening 31 for purposes explained later. Pivotally attached to the bolt 29 by means of the screw 32 is a catch 33 having the recess 34 and the knob 35. A rubber cushion 36 is carried by the plate 12 to abut upon the bolt 29 when it is in dependent position.

The door plate 37 is fixedly attached to the door 38 by means of the screws 39, 39, 39. The centering member 40 having an opening therethrough, carries the washer 41, the pivotal fastening latch 42, the washer 43 and the lock-ring 44. The casing 45 is threaded to the annular extension 46 of the door plate 37 and the whole affixed to the door 38 by means of the screw 47.

The fastening latch 42, which is pivotally carried by the door mechanism, comprises a bent arm 48 extended into an annular member 49 terminating in the knob, or ball, 50, which is slidable within slot 31 of the bolt 29, the ball 50 preventing its removal therefrom except at the upper portion of the slot.

The door 38 also carries the ordinary catch, or lock, 51.

The modification, shown in Figure 3, is adapted for use where the door is practically in the same plane as the door-frame, in which case, the angle of the member 48 of the fastening latch 42 is somewhat different from that described.

In the modification, shown in Figure 10, the fastening member is positioned by the side of the frame plate 12, instead of beneath it, as described. In this case, the fastening member 52 is pivotally attached to the door frame 50 by means of the screw 53 and extends outwardly 54 and then inwardly 55 having the concave member 56 to engage the bolt 29. A split-spring washer 57 is positioned between the fastening member portion 52 and the head 55 of the screw 53.

Figure 11 illustrates a washer 58, capable of being placed between the door 38 and the door plate 37, if necessary, to bring the door-plate mechanism in proper alignment with the bolt 29 to compensate for the depth of insertion of the door within the door frame.

The operation of the device is as follows:

When the device is in fastened position, as shown particularly in Figures 4 and 7, the bolt 29 is held in fixed perpendicular position

by means of the concave member 24 of the fastening member, thus preventing the movement of the fastening latch member 49 along the slot 31 of the bolt 29. The door 38 is thus securely fastened from an opening movement. 70

To partly open the door, the fastening member is revolvably removed from contact with the bolt 29, falling into the dot-and-line position indicated in prime numerals in Figure 4. The door 38 is then opened, thus moving the fastening latch 49 along the slot 31 of the bolt 29, and the catch 33 is revolved until the member 49 of the latch member is within the recess 34 of the catch 33, thus maintaining the door 38 in fixed open position. 75

In order to fully open the door 38, it is closed, the bolt 29 is moved in the plane of the door, but away therefrom, which allows the ball 50 of the latch to be removed from the slot 31 of the bolt 29, the latch being then raised into the dot-and-dash lines of Figure 4 and the door can then be opened. 80

From the above it will be noted that by means of my device, a door may be securely fastened in closed position, that the door may be fastened in a partly opened position and that the device can be positioned for the full opening of the door only when the door is in closed position. 90

It is evident, therefore, that when the door is in fastened open position, an intruder can not open the door further, because to do so, it is necessary to close the door which would bar him from tampering with the device. 100

I do not limit myself to the particular size, shape, number, arrangement, or material, of parts, as these are given simply as a means for clearly describing the device of my invention.

What I claim is:—

1. In a safety door-fastener, in combination, a frame-plate; an eye-shaped member extending from the frame-plate; a bolt having a longitudinal slot therein suspended from said eye; means for removably fastening the free end of the bolt of the frame-plate; a door-plate; a rigid pivotal latch carried by the door-plate, the free end of the latch being slidably movable within said slot and removable therefrom only at the suspending end of the bolt when the bolt is moved away from said latch and means for fastening the latch at a predetermined position within the slot. 110

2. In a safety door fastener, in combination, a frame-plate; an eye-shaped member extending from the frame-plate; means preventing the removal of the eye-member; a bolt having a longitudinal slot therein suspended from said eye; pivotal means for removably fastening the free end of the bolt to the frame-plate; a door-plate, a rigid pivotal latch carried by the door-plate, the free end of the latch being slidably movable within said slot and removable therefrom only at the suspending end of the bolt when the bolt is moved 125 130

away from said latch and pivotal means for fastening the latch at a predetermined position within the slot.

3. In a safety door fastener, in combination, 5 a frame-plate adapted to be attached to a door-frame; a bolt having a slot therein pivotally carried by the frame-plate; means for removably fastening the free end of the bolt to the frame-plate; a door-plate adapted to be attached to a door; a rigid pivotal latch carried 10 by the door-plate, the free end of the latch being slidably movable within said slot and not removable therefrom when a door to which the door-plate is attached is closed and 15 the free end of the bolt is in fastened position and means for fastening the latch in a predetermined position within the slot.

4. In a safety door fastener, in combination, 20 a frame-plate adapted to be attached to a door-frame; a bolt having a slot therein pivotally carried by the frame-plate; means for removably fastening the free end of the bolt to the frame-plate; a door-plate adapted to be attached to a door; a rigid pivotal latch carried 25 by the door plate, the free end of the latch being slidably movable within said slot and not removable therefrom when a door to which the door-plate is attached is closed and the free end of the bolt is in fastened position 30 and means for fastening the latch in a predetermined position within the slot when the door is in a partly open position.

5. In a safety door fastener, in combination, 35 a frame-plate adapted to be attached to a door-frame; an eye-shaped member extending from the frame-plate; a bolt having a longitudinal slot therein suspended from said eye;

means for removably fastening the free end of the bolt to the frame-plate; a door-plate adapted to be attached to a door; a rigid pivotal latch carried by the door-plate, the free end of the latch being slidably movable within said slot, said latch being non-removable from said slot when a door to which the door-plate is attached is closed and the free end of 40 the bolt is fastened and removable therefrom only at the suspending end of the bolt when the bolt is moved away from said latch and means for fastening the latch at a predetermined position within the slot. 45

6. In a safety door fastener, in combination, 50 a frame-plate adapted to be attached to a door-frame; an eye-shaped member extending from the frame-plate; means preventing the removal of the eye member: a bolt having a longitudinal slot therein suspended from said eye; pivotal means for removably fastening the free end of the bolt to the frame-plate; a door-plate adapted to be attached to a door; a rigid pivotal latch carried by the door-plate 55 the free end of the latch being slidably movable within said slot, said latch being non-removable from said slot when a door to which the door-plate is attached is closed and the free end of the bolt is fastened and removable therefrom only at the suspending end of the bolt when the bolt is moved away from 60 said latch and pivotal means for fastening the latch at a predetermined position within the slot. 65

Signed at New York city, in the county of New York and State of New York, this 22nd day of July, 1927.

CHARLES BRAND.
